CONNECTOR

Martin D. Bergan, Westfield, N. J., assignor to
 The Thomas & Betts Co., Elizabeth, N. J., a
 corporation of New Jersey

Application May 26, 1949, Serial No. 95,400

1 Claim. (Cl. 285—6.5)

1

This invention relates to a new and useful connector having a novel mode of operation affording increased convenience when installing it in service position, providing for longer life, and enhancing its reuse.

The principle of the invention lends itself to the improved manufacture of fittings for making electrical connections, the joining of rod members, and for effecting various forms of splicing and coupling operations, etc., where the fitting for these kindred purposes embodies a simple and known form of "screw-actuated clamping strap."

However, the example of the invention, as selected for disclosure and treatment herein, comprises a new connector useful for assembling raceways which enclose and insulate electrical-wiring installations, that is, for connecting BX cable, as well as conduit of various types, with electrical outlet and raceway boxes in general. Consequently, the example of the invention presented herein, as to its principle, relates to a "non-conductive" connector but is claimed in respect to all its adaptations and in any environment of its new "operating means" for more efficiently handling the old type "screw-actuated clamping strap" above mentioned.

Among other uses for the invention, its outright simplicity finds immediate application in solving a long existing problem in electrical-raceway connectors, specifically the "screw-actuated clamp strap" type (also known as "squeeze" type) cable connectors for flexible-metallic conduit as well as BX cable. Such connectors are employed for assembling conduits which enclose the electrical conductors of power and lighting circuits. Raceway connectors of the species improved upon herein are well known in the art.

The prior art contains raceway connectors for the commonly known BX cable and flexible-metallic conduit, both of which have spirally-armored conductors ordinarily called "cable" in the trade. Thus, for convenience, the term "cable" herein may as well be used generically to mean both types of spiral-armor, if not indeed electrical conductors as such, since the invention finds utility not only in improving non-conductive raceway fittings but may also be employed in the electrical connector field as well.

Prior cable connectors of the species in question—all alike in principle but differing somewhat in structural form—have a screw-actuated clamping or squeezing strap which fastens the cable (spiral-armor) in the tubular body of the

2

connector. In general, the old type of clamping screw turns with considerable friction and wear because the movable clamping strap varies its angle of engagement with the head of the screw. Thus the plane of the swingable clamping strap, intersecting the axis of the rotating screw, constantly changes its angle of intersection. A "side force" is thus exerted by the old type clamping strap at an angle against its screw, thereby reducing the efficiency of the screw and presenting the problem which this invention seeks to solve.

In further explanation of the problem herein, it is next pointed out that the above recited 15 "side force"—acting on the screw at an angle to its axis—tends to tilt the screw off of its normal axis of rotation. Such abnormal misalignment (or the angular force tending to cause same) generates friction in the rotating screw-threads, thus requiring excess effort of a workman for turning the screw, and causing wear of the screw-threads, thereby reducing the reusable life of the connector.

In many instances, the present-day cable connector is difficult to install—for in forcing its 25 rotation by a screwdriver, the threads may be "crossed" or worn or chipped. Thus damaged, the connector may fail to maintain its required degree of clamping pressure on the cable, may 30 have a short life, and if removed from the installation is not fit for reuse. Actually, any screw, which is not guided on its normal axis of rotation, is twice subjected to wear and tear not only of its threads but also the threads of the 35 member which it engages—once when screwed inwardly under pressure and again when removing the screw.

While the foregoing explanation of the problem is brief, and does not outline all the causes 40 and effects arising out of the geometrical variation of the forces involved, the matter is believed clear to those conversant with this branch of the prior art, especially so after further study of the teachings herein and a comparison of this 45 new connector with representative types known to the art. Accordingly, the invention may now be more fully considered, its purpose, and how it solves the problem.

The purpose of the invention is to provide a 50 novel "operating means" for screw-actuated clamping strap devices which resolves all angular force components along a single straight line, that is, along the axis of screw rotation, thereby freeing the screw of "side force"—introducing no force at an angle to its axis—thus permitting

the screw to perform its dual motion (combined rotation and longitudinal travel) exactly along the axis not only of its own threads but also the axis of the screw-threaded hole in which it is operatively mounted.

Thus stated, one will appreciate by study and comparison that the accomplishment of the foregoing purpose inhibits all forces tending to "tilt" or displace the screw off the two axes, that of its own threads and that of the threads which it operatively engages. Accordingly, the screw of the new "operating means" herein is so improved by reason of its new operating environment that it rotates and longitudinally travels in and out of clamping pressure with a minimum of friction and wear.

It follows, therefore, that a given torque of the screwdriver, during installation, is fully utilized in driving the screw home. In other words, a percentage of the active torque is not dissipated in wearing or fracturing the screw-threads. Such improvements in function make for convenience of installation. Also, the screw has longer life and is adapted for numerous reuses, by reason of its freedom from wear and tear, as will be appreciated by considering one important structural example of the invention illustrated herein. The accompanying drawings with description and claim explain the invention as preferred and embodied at this time for an understanding of the problems sought to be solved. Since the teachings herein may suggest structural changes to others who wish to avail themselves of the benefits of the invention, it is pointed out that subsequent modifications hereof may well be the same in spirit and principle as this disclosure.

The original Patent Office drawings, constituting a part hereof, are made to three times the scale of a "3/8 Trade Size" commercial production specimen of the connector. Thus, the official drawings show the connector to scale from which not only the proportions but the actual dimensions are available as a part of the disclosure.

Fig. 1 shows a side elevation of the connector, with its clamping strap and novel operating means therefor carried on the rear (outer) end of the tubular body, in wide open position, for receiving a maximum size cable, or large size electrical conductor, or other member, adapted to be connected with and by this fitting.

Fig. 2 shows a transverse section on the line 2—2, across the rear end of the connector, looking toward the front (inner) end, with its clamping screw partly withdrawn, in order to illustrate more clearly the screw-threaded hole at the lower right hand side of the view, an important consideration herein.

Fig. 3 shows a top view of the connector clamped on a piece of BX cable or a piece of flexible-metallic conduit (spiral-armor) of the maximum size adapted to be received by the fitting.

Fig. 4 shows a transverse section on the line 4—4, thus being a rear end view looking toward the front end of the connector, with the maximum size piece of cable clamped therein.

Fig. 5 also is a transverse section similar to Fig. 4, except showing a minimum size cable secured in the connector.

Figs. 4 and 5 are comparison views which demonstrate the range of sizes of cable, conduit, electrical conductors, or other members, which are adapted to be connected with or by this fitting. Thus, a maximum size cable is shown in Figs. 3 and 4, while a minimum size thereof is seen in Fig. 5. It will be understood that in practice

there are a number of intermediate sizes of cables, etc., which may be used with this connector.

Figs. 2 and 3 include dot-and-dash lines A, etc., indicating the axes of certain parts of the new connector, in aid of explaining the concept of invention herein.

Referring further to the drawings for a more detailed description of the invention, it will be understood by those conversant with the art that cable connectors of the type in question comprise a tubular body, the front end 10 of which is usually screw-threaded. This end portion 10 is adapted to be inserted into a raceway opening (such as a conduit box hole), with an annular shoulder 11 abutting the outside surface of the box, and the tubular body secured in the box by a lock nut tightened onto the threaded end 10. Such conventional raceway parts, as the box and nut, etc., are well understood and omitted from the drawings for clarity.

An ear 12 is carried on the rear end of the tubular body, with a screw-threaded hole 13 provided through the ear outside the body circumference. In this example of construction, the ear is integral with the tubular body at the circumference of the latter. The ear is comparatively rigid in order to maintain the screw-threaded hole 13, and hence its axis, in a position fixed (as near as may be possible) against displacement when under clamping strain. Thus the axis of the threaded hole 13 stands perpendicular to the axis of the tubular body.

An arcuate clamping strap 14 is also carried on the rear end of the tubular body 10 as, for example, by forming the inner end of the strap integrally with the body on the circumference thereof. This strap is separated from the rear end of the body by a narrow clearance slot 15 in order that the strap may bend and swing inward of the body circumference. One or more weakening notches 16 may be provided in the arcuate strap near its integral end, as a means for inducing the strap to bend near its inner end (see Fig. 5) when its outer free end is drawn toward the ear 12 for clamping a cable C, or other like member, within the connector body 10.

The outer free end of the clamping strap 14 is provided with a screw-clearance aperture 18 outside the circumference of the tubular body and in axial alignment, that is, coaxially with the screw-threaded hole 13 of the rigid ear 12. It is observed that the arcuate clamping strap 14 is formed from a long segment of the circumference of the tubular body, while the ear 12 comprises a short or stub segment thereof. Thus the longer reach of the strap makes it bendable toward the ear, the latter being short to impart stiffness thereto so as to remain stationary against pulling force of the strap.

Incidentally, the tubular body 10 is usually formed of malleable stock as, for example, sheet steel or the like (when manufacturing connectors for raceway use and other non-conductive utility), thus providing for inward bending or flexure of the clamping strap 14 at its inner-integral end portion where it is notched at 16 to facilitate bending motion. The action of the strap is shown by the comparison views (Figs. 4 and 5) demonstrating the considerable range in sizes of spiral-armor cables C to which the strap is adapted for clamping movement toward the rigid and stationary ear 12.

The foregoing description and parts are largely conventional and constitute one exemplary environment or setting for the invention, as next

described herein, by which a new combination is attained, characterized by a novel mode of operation, and resulting in functional improvements beneficial to the art.

A headed-clamping screw is operatively mounted in the arcuate clamping strap 14 and rigid ear 12. Thus a common screw has its threaded shank 19 rotatably mounted through the enlarged screw-clearance aperture 18 of the outer free end of the movable clamping strap 14, and its shank extremity is threadedly engaged within the screw-threaded hole 13 of the rigid ear 12. A screw head 20 on the end of the threaded shank 19 is somewhat larger than the clearance aperture 18 and thus bears against the outer free end of the clamping strap, doing so in a characteristic manner next described.

An ordinary machine screw (in the interest of production economy) is well adapted for use in this new connector, and commonly has its head formed with an inside flat surface, as at 20, availed of by the invention.

A bearing-crown is die-formed or otherwise provided at 21 on the outer free end of the clamping strap 14, symmetrically on both sides of the screw-clearance aperture 18, and against which the screw head 20 rides under pressure during tightening operation. This characteristic feature comprises a lengthwise ridge or longitudinal-crest which is outwardly ovalled or ridge-crowned by a smooth semi-circular frictionless surface formed outside of the circumference of the tubular body and outward or away from the rigid ear 12. It is noted that the crest-formation of the bearing-crown 21 and the screw-threaded ear 12 are spaced from each other outside the circumference of the tubular body and that the axes of the screw-clearance aperture 18 and the screw-threaded hole 13 are in alignment. These geometrical aspects of the new connector operating means are best emphasized by next referring to the three axis lines A, etc., on the drawings.

In Fig. 3, the longitudinal axis of the tubular body 10 is indicated by a dot-and-dash line BA, while the longitudinal bearing-crown 21 has its axis along a dot-and-dash line CA. Thus, it is seen that the body axis BA and the crown axis CA are parallel which is important concerning the new operating means herein for the clamping strap 14. Then in Fig. 2, the axis of the threaded shank 19 of the clamping screw is indicated by a dot-and-dash line 3A, this axis line also indicating the common center lines or axes of the enlarged screw-clearance aperture 18, as well as the screw-threaded hole 13. Thus all three last-named portions (the screw 19, the aperture 18, and the hole 13) have a common axis 3A which is perpendicular to the tubular body axis BA as well as the bearing-crown axis CA.

According to the foregoing description and study of the accompanying drawings, it is observed that the inner flat surface of the screw head 20 rotatably engages the oval-lengthwise crest of the bearing-crown 21 with minimum-area pressure engagement when drawing the resisting clamping strap 14 from its outer position (Fig. 2 or 4) to its inner position (Fig. 5). The minimum-area of pressure engagement, between the plane of the screw head 20 and the bearing-crown 21, affords easy and near frictionless operation of the clamping screw during its dual motion of rotation and longitudinal travel in relation to the screw-threaded hole 13. This is accomplished by reason of the fact that

the novel bearing-crown 21 makes for constant tangential engagement between the screw head 20 and the clamping strap 14 for all changing positions of the latter throughout its range of movement.

The bearing-crown 21—being equally or symmetrically disposed on both sides of three axes 3A in common (Fig. 2), also acting at all times near or substantially on said axis, and in tangent relation to the screw head 20—functions to equalize the angular reaction and the bending resistance of the clamping strap 14, as it is drawn inwardly, and causes said strap to resolve its angular component and apply its force in a constant direction against the screw head, to-wit, coaxially thereof along said axis 3A. Of importance is the fact that the bearing-crown 21 acts to resolve the changing angular reaction of the clamping strap 14 into a single force component which is uniformly and constantly coaxial with the three common axes 3A, thereby avoiding any exertion of an angular force against the threaded shank 19 of the clamping screw. Such operation is free of all tilting force or side stress and permits the threaded shank 19 freely to rotate and travel in or out, along the common axis 3A (of the screw shank 19, the clearance aperture 18, and the threaded hole 13), hence uniformly and evenly along said axis of the threaded hole with a minimum of friction therein. Accordingly, there exists a minimum of wear and damage to both sets of screw-threads 13 and 19 of the connector.

By comparing the several positions which the bearing-crown 21 assumes in relation to the center of the screw-head 20 (using the axis line 3A as a reference), throughout the range of operation of the clamping strap 14 (Figs. 2, 4 and 5), it will be observed that the crest of said bearing-crown creeps slightly from one side of the axis line to the other side thereof, but that it equalizes on each side and maintains pressure engagement tangent to the plane of the flat-bearing area 20 of the screw head.

Now it is observed how closely the bearing-crown axis CA hugs the tri-axes 3A throughout the cable-sizes range of operation. For the large size cable C (Figs. 3 and 4), it is seen that the axis CA of the clamping strap bearing-crown 21 intersects the axis 3A; hence the resistance of the strap 14 is exerted coaxially of the screw-threaded hole 13, which is an ideal operating condition achieved by the invention. And for small size cable, the crown axis CA holds so closely to the tri-axes 3A that side or tilting force on the screw shank 19 is negligible.

The foregoing new mode of operation provides an easy turning screw head and shank, makes for convenience in installing the connector, better adapts it to a range of cable sizes, particularly for small size cable (Fig. 5), does not require excess screwdriver torque to tighten the clamping strap 14, preserves the screw threads 13 and 19, increases the life of the connector, and enhances its overall utility for reuse if and when removed from an original installation.

This disclosure explains the principles of the invention and the best mode contemplated in applying such principles, so as to distinguish the invention from others; and there is particularly pointed out and distinctly claimed the part, improvement or combination, which constitutes the invention or discovery, as understood by a comparison thereof with the prior art.

The invention is presented to fill a need for

a new and useful connector. Various modifications in construction, mode of operation, use and method, may and often do occur to others, especially so after acquaintance with an invention. Accordingly, it is to be understood that this disclosure is exemplary of the principles herein and embraces equivalent constructions.

What is claimed is:

In a connector of the type having a tubular body adapted to receive a cable, with a rigid ear carried on the tubular body and provided with a screw-threaded hole, a clamping strap having its inner end carried on the body and its outer end free for movement toward the rigid ear, the outer free end being provided with a screw-clearance aperture which is coaxial with the screw-threaded hole, and operating means for drawing the clamping strap toward the rigid ear, including a headed-clamping screw having a threaded shank mounted through the screw-clearance aperture and threadedly engaged within the coaxially screw-threaded hole of the rigid ear, and also including and being characterized by a bearing-crown, in the form of a longitudinal-crest, provided on the outer free end of the clamp-strap, with said longitudinal-crest disposed outward from the rigid ear, and on both sides of the screw-clearance aperture, as well as along an axis parallel with the axis of the tubular

body, and against which a minimum area of the inner surface of the head of the clamping screw has tangential engagement; whereby the screw head rotates with a minimum of friction when drawing the clamping strap toward the rigid ear to grip the cable within the tubular body, and the bearing-crown acts under the force of the tangent screw head to maintain the reaction of the clamping strap substantially coaxial with the screw-threaded hole of the rigid ear, at and for all positions assumed by said screw head and said clamping strap, throughout their range of operation, whether gripping large size or small size cable, by which the threaded shank also rotates with a minimum of friction, as well as freedom from wear, within the screw-threaded hole.
